UNITED STATES PATENT OFFICE.

MATTS SKOW, OF OMAHA, NEBRASKA, ASSIGNOR OF TWO-THIRDS TO LAWRENCE C. ENEWOLD AND EDWARD PETERSON, OF SAME PLACE.

HARROW.

SPECIFICATION forming part of Letters Patent No. 397,145, dated February 5, 1889.

Application filed November 14, 1887. Serial No. 255,169. (No model.)

To all whom it may concern:

Be it known that I, MATTS SKOW, a citizen of the United States, residing at the city of Omaha, in the county of Douglas and State of 5 Nebraska, have invented a certain new and useful Improvement in Agricultural Implements known as "Harrowes;" and I do declare that the following is a full, clear, and exact description of the invention.

10 My invention relates to rotary harrows, and is especially designed as an improvement on those harrows in which a laterally-extending arm is provided with a weight arranged to overhang and bear down one side of the toothed frame, so that the teeth of the latter will more forcibly engage the earth upon one side than upon the other, whereby the frame is caused to rotate as it advances.

15 The object of my invention is to provide improved means for supporting and adjusting the angle of the weighted arm, whereby the construction and operation of the mechanism can be made superior to those hitherto in use.

20 With these ends in view my invention consists in the peculiar features more fully described hereinafter, and pointed out in the claim.

25 Referring to the accompanying drawings, Figure 1 represents a plan of my complete device, and Fig. 2 a side elevation of the same.

30 The main frame A of the harrow is circular in general outline, and is composed of a series of concentric rings, B, to the under side 35 of which are secured the lattice-bars C. These bars are arranged at right angles to each other, and at their points of intersection are bolted together by means of the threaded 40 shanks D of the teeth E, which pass through them, and to these shanks the nuts F are applied, and the frame thus rigidly secured together. This construction being well known, it will not require further description.

45 The draft-bar G is pivoted to the center bolt, H, and the brace-bar I, which is also pivoted to the center bolt, holds the draft-bar rigidly in place and prevents undue wear and strain. The weighted arm J is also pivoted 50 to the central bolt, H, and provided with a

brace-bar, K, pivoted at the top of the bolt in the manner similar to that of the draft-brace I. The eyes L of the draft-bar and weighted arm rest one upon the other, and both bear upon the central seat, M. N represents a 55 thin curved bar secured rigidly to and rotating with the draft-bar. This bar N extends around parallel with the concentric rings B, and its free end passes through an aperture, O, in the weighted arm J, and the latter is 60 locked at various angles to this bar by the set-screw P. It will be observed that the bar does not form a complete circle, but is abbreviated, being merely semicircular, which construction is for the purpose of saving material. The weight W upon the free end of the regulating-arm is provided with a hole, Q, through which the arm passes, so that it can be adjusted nearer to or farther from the center of the machine, for the purpose which 65 will be presently mentioned. The thumb-screw R upon the top of the weight enables the latter to be locked at any desired point upon the arm.

70 The top of the center bolt, H, to which the draft-bar and regulating-arm are pivoted, is provided with a screw-thread which receives the nut S for locking these two parts down upon the bolt. It will thus be apparent that when the plane of the arm is set at an angle to 75 the path or direction in which the machine is moving the center of gravity will lie between the central axis of the rotating frame and cause the weight to preponderate upon that side of the machine. Consequently the teeth 80 upon the weighted side are made to penetrate deeper into the earth and rotate the frame in the manner well known to the art; but by my special arrangement the depth penetrated by the teeth, and consequent velocity with which 85 the frame rotates, can be regulated to the utmost nicety. When the adjustable weight W is placed a considerable distance out upon the arm J and the latter is locked at right angles 90 to the draft-bar, as shown in Fig. 1, then the teeth will penetrate deeply into the soil and rotate the harrow at a greater velocity; but when it is desired to diminish the depth at which the teeth penetrate the curved bar N 95 can be unlocked and swung around to a less 100

angular position, as shown in dotted lines in Fig. 1, and if not adjusted to the proper penetration the weight can be moved a suitable distance backward or forward upon the arm J.

5 The advantages of this arrangement over those formerly in use are that the degree of penetration of the teeth can be regulated to suit the strength of the animal drawing it, the kind of grain sown, the soil acted upon, or, in fact, any of the exigencies of the case.

Having thus described my invention, what I claim as new, and desire to secure by Letters Patent, is—

15 The combination, in a rotary harrow, of a rotary frame provided with a central pivot, a draft-bar and weighted arm centered upon

said pivot, brace-bars rigidly secured to the draft-bar and weighted arm, respectively, and pivoted to the central pivot, a semicircular bar rigidly secured to the draft-bar and in engagement with the weighted arm, and a setscrew for locking the semicircular bar to the weighted arm, all arranged and adapted to operate substantially as described.

Dated at Omaha, in the county of Douglas 20 and State of Nebraska, this 4th day of November, A. D. 1887.

MATTS SKOW.
